UNITED STATES PATENT OFFICE.

PHILLIP F. POORBAUGH, OF ALLEGHENY, PENNSYLVANIA, ASSIGNOR TO
THE PITTSBURG COAL MINE SUPPLY COMPANY, OF PENNSYLVANIA.

MINERAL-SCREEN.

SPECIFICATION forming part of Letters Patent No. 655,160, dated July 31, 1900.

Application filed August 24, 1898. Serial No. 689,382. (No model.)

To all whom it may concern:

Be it known that I, PHILLIP F. POORBAUGH, a citizen of the United States of America, residing at Allegheny, in the county of Allegheny and State of Pennsylvania, have invented certain new and useful Improvements in Mineral-Screens; and I do hereby declare the following to be a full, clear, and exact description thereof, reference being had to the accompanying drawings, which form a part of this specification.

My invention relates to certain new and useful improvements in mineral-screens, and has for its object to construct a screen of this character in which the screen-plate and its shoe are arranged at an angle, are vertically adjustable, and are pivotally connected near their upper ends to a suitable supporting-frame. The plate and its shoe are operated by suitable mechanism arranged at one end of the supporting-frame.

With the above and other objects in view the invention consists in the novel construction, combination, and arrangement of parts hereinafter more specifically described, and particularly pointed out in the claims hereunto appended.

In describing the invention in detail reference is had to the accompanying drawings, forming a part of this specification, wherein like numerals of reference indicate corresponding parts throughout the several views thereof, in which—

Figure 1 is a side view of my improved screen. Fig. 2 is a top plan view thereof with a portion of the bottom of screen-plate broken away. Fig. 3 is a cross-sectional view taken on the line xx of Fig. 1. Fig. 4 is an enlarged cross-sectional view of the self-oiling shaft. Fig. 5 is a top plan view of the pivoted adjustable mechanism for the screen-plate and its shoe. Fig. 6 is a side view of a portion of the operating mechanism for the screen-plate and its shoe. Fig. 7 is a cross-sectional view, partly broken away, taken on the line yy of Fig. 1.

Referring to the drawings by reference-numerals, 1 indicates a suitable supporting-frame having journaled in its lower end the operating-shaft 2, which extends transversely across the frame. This shaft 2 also extends

outwardly on each side of the frame 1, as shown; and has mounted on one end the rigid pulley 3 and the loose pulley 4, and on its opposite end is mounted the fly-wheel 5. Suitably arranged upon the shaft 2 is a pair of operating-cams 6, which are secured in position by means of the keepers 2'. The inner face of the sides of the frame 1, near the upper end thereof, has secured thereto a pair of guide-plates 7, which are arranged a suitable distance apart and between which operates an adjustable slide-plate 8, having on its inner face the boss 8' and an upwardly-extending apertured lug 7'.

Journalized in the boss 8' is a transversely-extending shaft 9, to which is pivotally secured by means of the hanger 9' (only one shown) the screen-shoe 10, provided on its inner face with the ridge or shoulder 10', upon which is secured in any suitable manner the screen-plate 10'.

The slide-plates 8 are adjusted by means of the upwardly-extending screw-threaded bolt 11, operating through the apertured lug 7', as shown, and also through the guide or keeper 12, secured to the outer face of the sides of the screen-shoe 10.

12' indicates the adjusting-nut, which is mounted upon the bolt 11, as shown, the movement of which is arrested by means of the guide or keeper 12.

Secured to the inner face of each side of the frame 1 a suitable distance from the slide-plate 8 is a bracket 13, in which is mounted the upwardly-extending screw-threaded bolt 15. This bolt 15 operates through the keeper or guide 14, secured to the outer face of the screen-shoe 10, and has mounted thereon the coiled tension-spring 16 and adjusting-nut 17.

The underneath face of the screen-shoe 10 at its lower end is provided with the downwardly-extending hangers 18 for supporting the self oiling or lubricating shaft 19, which is hollow and has the outlets 22 (only one shown) for discharging the lubricating material. Connected to one end of the shaft 19 is the lubricating-supply pipe 23, provided with a suitable closure-cap 24.

Mounted upon the shaft 19 over the openings 22 is a pair of antifriction-rollers 20, which are in direct alinement with the cam 6 upon

the shaft 2. 21 indicates a rubber bumper, which is also mounted upon the shaft 19 and between the antifriction-rollers 20.

The operation of my improved device is as follows: The rectangular frame 1 being arranged at an inclination, power is applied to revolve the shaft 2, carrying the cams 6 6 therewith, elevating the screen 10" by the contact of the cams 6 with the antifriction-rollers 20. This elevating movement of the screen-shoe will be discontinued when the smallest portion of the cam is reached, and the screen will then fall upon the bumper 21. This movement of the screen-shoe will cause the material to travel rapidly, as well as screening the same. During the fall of the end of the screen-shoe the oil contained in the shaft 19 will be agitated and cause a sufficient quantity to be forced up through the openings 22 and lubricate the antifriction-rollers.

It will be evident that to increase or diminish the inclination of the screen-shoe the same can be obtained by the adjustment of the nuts 12' upon the bolts 11 and that, if desired to cause the fall or the lowering of the screen-shoe more rapidly, the tension of the spring 16 can be regulated by means of the nut 17, operating against the same.

30 The action of the top or upper end of the screen plate and shoe above the shaft 9 is a lifting movement and is less active than the longer part below the shaft, as the shoe receives the jar from the action of the cams at 35 its opposite end, this being quite a different movement to the lifting motion of the upper end, and the spread and throw of the material may thereby be kept under control.

Having fully described my invention, what 40 I claim as new, and desire to secure by Letters Patent, is—

1. In a screening device, the combination of a supporting - frame, an operating - shaft mounted in the lower end thereof, cams suitably mounted on said shaft, a screen-shoe provided with a suitable screen-plate and operated by said cams, guides connected to the inner face of each side of said frame, slide-plates mounted in said guides, a shaft 9 jour-

naled in said slide-plates and with which the 50 shoe is pivotally connected at its upper end, and vertical adjusting means connected to each of said slide-plates and to the said screen-shoe, substantially as described.

2. In a screening device, the combination, 55 of a supporting - frame, an operating - shaft mounted in the lower end thereof, cams suitably mounted on said shaft, a screen - shoe provided with a suitable screen-plate and operated by said cams, guides connected to the 60 inner face of each side of the frame, slide-plates mounted in said guides, a shaft 9 mounted in said slide-plates and with which the shoe is pivotally connected at its upper end, vertical adjusting means connected to 65 each of the said slide-plates and to each side of the shoe, and a tension device arranged at each side of the said frame and connected to said shoe, substantially as described.

3. The combination of a supporting-frame 70 having an operating-shaft arranged at the lower end thereof, a pair of cams mounted on said shaft, a screen-shoe provided with a suitable screen - plate, guides connected to the inner face of each side of the supporting- 75 frame, a pair of slide-plates arranged to move vertically in said guides, a shaft 9 mounted in said slide-plates and with which the said shoe is pivotally connected at its upper end, a self-lubricating shaft connected to the under 80 face of the lower end of said screen-shoe, anti-friction-rollers mounted on the lubricating-shaft and adapted to be engaged by the said cams for elevating the screen-shoe, vertical 85 adjusting means connected to the said slide-plates and to each side of the screen-shoe, a tension device arranged at each side of the said frame and connected to said shoe, and a bumper suitably mounted on said lubricating-shaft, substantially as described. 90

In testimony whereof I have hereunto affixed my signature in the presence of two subscribing witnesses.

PHILLIP F. POORBAUGH.
